Des. 223,360

Patented Apr. 11, 1972

223,360

HOUSING FOR COMMUNICATIONS TERMINAL

Charles J. Ortega, Van Nuys, and Frederic L. Naff, Jr.,
Los Angeles, Calif., assignors to Computer Transmission
Corporation, Los Angeles, Calif.

Filed Feb. 4, 1970, Ser. No. 21,267

Term of patent 14 years

Int. Cl. D14—01

U.S. Cl. D26—5

FIG. 1.

FIG. 2.

FIG. 3.

FIG. 1 is a perspective view of the housing for communications terminal of this invention;

FIG. 2 is a side elevational view of the housing for communications terminal of FIG. 1; and

FIG. 3 is a front elevational view of the housing for communications terminal of FIG. 1.

The undisclosed rear portion of the housing follows the general outline of the rear sides as best illustrated in FIGS. 1 and 2 on the drawing.

We claim:

An ornamental design for a housing for communications terminal, substantially as shown and described.
